(57) **CLAIM**

The ornamental design for a ceiling fan with light fixture, as shown and described.

DESCRIPTION

FIG. 1 is a perspective view of a ceiling fan with light fixture in accordance with my design;

FIG. 2 is a top plan view of the ceiling fan with light fixture in accordance with my design wherein the mount is removed for ease of illustration;

FIG. 3 is a bottom plan view of the ceiling fan with light fixture in accordance with my design;

FIG. 4 is a side elevation view of the ceiling fan with light fixture in accordance with my design, the opposite side being identical thereto; and,

FIG. 5 is a front elevation view of the ceiling fan with light fixture in accordance with my design, the rear view being identical thereto.

The broken-line disclosure of elements is understood to represent portions of the article in which the design is embodied, but which form no part of the claimed design.
